UNITED STATES PATENT OFFICE.

WILLIAM W. SLY, OF CLEVELAND, OHIO.

DESIGN FOR A HANDLE FOR STOVE-LID LIFTERS, &c.

SPECIFICATION forming part of Design No. 19,156, dated June 11, 1889.

Application filed April 23, 1889. Serial No. 308,338. Term of patent 3½ years.

To all whom it may concern:

Be it known that I, WILLIAM W. SLY, a citizen of the United States, residing at Cleveland, in the county of Cuyahoga and 5 State of Ohio, have invented and produced a new and original Design for a Handle for Stove-Lid Lifters, of which the following is a specification, reference being had to the accompanying drawing, forming part thereof.

10 The figure represents a stove-lid-lifter handle embodying my new design.

The new feature of my design is the form and configuration of the handle, which consists in open-work, comprising longitudinal 15 bars or rods *a a* and the representation of

spirally-wound bands *b b*, encircling said bars, extending from point to heel, forming a latticed tubular handle.

Having described my design, what I claim is—

20 The design for a handle herein shown and described, the same consisting of the longitudinal bars or rods *a a* and the spiral bands *b b*, encircling the bars, forming the latticed tubular handle.

WILLIAM W. SLY.
